UNITED STATES PATENT OFFICE

EDSON G. WHITCOMB, OF KEENE, NEW HAMPSHIRE, ASSIGNOR TO SPRAGUE & CARLETON, OF KEENE, NEW HAMPSHIRE, A CORPORATION OF NEW HAMPSHIRE

DESIGN FOR A CHAIR OR SIMILAR ARTICLE

Application filed February 12, 1930. Serial No. 34,491. Term of patent 7 years.

To all whom it may concern:

Be it known that I, Edson G. Whitcomb, a citizen of the United States, residing at Keene, in the county of Cheshire and State of New Hampshire, have invented a new, original, and ornamental Design for Chairs or Similar Articles, of which the following is a specification, reference being had to the accompanying drawing, forming part thereof:

Fig. 1 is a perspective view of a chair showing my new design.

Fig. 2 is an enlarged fragmentary view of Fig. 1.

The entire seat of the chair is of cane fabric.

I claim:

The ornamental design for a chair or similar article as shown and described.

EDSON G. WHITCOMB.
